(57) **CLAIM**

(21) Appl. No.: **29/290,077**

The ornamental design for a frontal configuration of a steering wheel, as shown and described.

(22) Filed: **Oct. 17, 2007**

DESCRIPTION

(30) **Foreign Application Priority Data**

Apr. 18, 2007 (DE) 40702112

FIG. 1 is a front view of a frontal configuration of a steering wheel according to my novel design; and,

(51) **LOC (8) Cl.** **12-16**

FIG. 2 is a left perspective view thereof, the right perspective view being mirror symmetrical.

(52) **U.S. Cl.** **D12/176**

The broken lines are for illustrative purposes only and form no part of the claimed design.
